HARALD BILLE, OF CROYDON, ENGLAND, ASSIGNOR TO CREED, BILLE & CO., LTD., OF CROYDON, ENGLAND.

AUTOMATIC TRANSMITTER FOR TELEGRAPHIC SIGNALS.

1,098,084.

Specification of Letters Patent.

Patented May 26, 1914.

Application filed March 27, 1913. Serial No. 757,178.

To all whom it may concern:

Be it known that I, HARALD BILLE, a subject of the King of Denmark, residing at Croydon, in the county of Surrey, England, 5 have invented certain new and useful Improvements in Automatic Transmitters for Telegraphic Signals, of which the following is a full, clear, and exact description.

The invention relates to automatic transmitters for telegraphic signals of the kind in which contact making parts are controlled by a perforated paper slip, and the new apparatus can be used in the same manner as the usual transmitters for closing, interrupting and reversing of signal currents in land-line or cable-telegraphy, or for effecting or controlling the movements of contacts for the closing and interrupting of strong currents in accordance with the telegraph signals for the transmission of signals in wireless telegraphy, where great quantities of energy are sometimes to be controlled.

The invention in its preferred form will now be fully explained in connection with 25 the annexed drawing, in which—

Figure 1 shows the essential parts of an ordinary well known so called Wheatstone transmitter, and Fig. 2, the new and improved form for such transmitter.

30 In Fig. 1 there is shown the well known form of Wheatstone transmitter such as is described in T. E. Herbert's book on telegraphy, published in London by Whittaker and Co., in 1906, and in which *a* designates a star-wheel which is provided with teeth adapted to co-act with the roll *b*, the teeth of the star-wheel engaging the central row of holes in the well known Wheatstone perforated slip. A rocking beam *c* is connected 35 to the star-wheel *a* by any suitable gearing (not shown) so that when the rocking beam is caused to move up and down it will be moved at a speed which conforms to the rate of speed at which the star-wheel moves the 40 perforated slip through the instrument, the rocking beam being actuated by means of any well known form of mechanism for that purpose, one of such mechanisms being described in the book referred to. Two rods *e* and *f*, are fixed to the horizontal ends of the levers *g* and *h*, which are pivoted at *i* and *k* on the front of the machine, and are subjected to an upward pressure by means of the spiral springs *m* and *n*. The two rods *e* and *f* are arranged one opposite each of the 45 two lines of larger holes in the punched tape, so that their ends will project through the paper in case a hole is found or will be stopped by the paper if no hole is found. The rod *e* projects through the holes in the 50 lower row of the slip, and the rod *f* through those in the upper row. The adjustable studs *o* and *p* and the spiral springs acting upon the rods *e* and *f* keep them in the correct position. While the sprocket wheel *a* 55 feeds the tape forward a length equal to the distance between two consecutive feed holes the beam makes a complete oscillation. Projecting from the beam *c* are two steel pins *q* and *r* against which the levers *g* and *h* are 60 normally held by the springs *m* and *n*, so that the levers are kept rocking in unison with the rocking beam *c*. The lever *g* has at its lower end a rod *s* pivoted to it, and the lever *h* is connected at its upper end to a 65 similar rod *t*. The free ends of these rods pass freely through holes in the arms *u* and *v* of the rocking lever *x*, and upon them are screwed adjustable collars *y* and *z*. The lever *x* consists of an ebonite disk on which 70 are mounted the steel levers *u* and *v* and the two brass plates carrying the pins 1 and 2. These brass plates are insulated from each other by ebonite, and a long thin coil of wire connects them respectively to the brass 75 contacts 3 (line) and 4 (earth). The pins 1 and 2 rock between the bellcrank levers 5 and 6, making contact with either alternately. These bell-crank levers are kept apart by a small screw 7 fixed in the lever 5 80 and abutting on a jewel set in the lever 6. The levers 5 and 6 are respectively connected with the positive and the negative poles of the battery. The four brass mountings 3, 8, 9 and 4 are insulated from each other, by 85 being mounted on a plate of ebonite 10. The springs 11 and 12 keep the bellcranks 5 and 6 together and against the pins 1 and 2. They are of course kept a distance apart 90 greater than the diameter of the said pins by 95 means of the screw 7. The travel of the rocking lever *x* is limited by the abutment screws 13 and 14, while a sharp and definite action on either side or the other with strong contacts is secured by means of the jockey 100 pulley 15 riding on the point of the steel arm *v*. The action of this well known apparatus is as follows: When the transmitter is set in motion the rocking beam *c* vibrates 105 and the pins *q* and *r* move alternately up 110

and down. When the pin *q* rises, the horizontal arm of the lever *g* is free to rise also, and the spring *m* causes it to do so. The rod *s* is thereby moved toward the right and the 5 collar *y* pushes the arm *u* of the rocking lever *x* toward the right. The pin *r* simultaneously descends, pressing the lever *h* down and moving the collar *z* clear of the arm *v*. When the pin *r* rises in its turn, 10 the reverse action takes place, the rod *s* being moved to the left so that the collar *y* is clear of the arm *u* and the rod *t* being moved to the right so that the collar *z* pushes the upper arm *v* smartly to the right. It will 15 thus be remarked that the whole of the work for moving the parts making and breaking the contacts for reversing the current is done by the springs *m* and *n*, the rocking beam *c* being used only to tighten 20 them and remove some of the obstacles in the way; (all the positive work for moving the contacts is taken from the said springs).

The new machine shown in Fig. 2 has 25 essential parts similar to those of the old transmitter and such corresponding parts are designated by the same reference letters in the two figures.

The main spindle carries a crank 16 co- 30 acting with a connecting rod 17. The main spindle is as in the machine shown in Fig. 1 geared to the feed wheel *a*; thus for every feeding of a feed hole by the wheel *a* a complete oscillation of the connecting rod 17 and of the parts attached thereto is effected. 35 The connecting rod 17 is fixed at 18 by a pin to the three-armed lever 19. This lever, by means of the link 20, pivoted to one arm thereof and to the pin 22 on the rocking beam *c*, communicates to the latter oscillations derived from the crank 16. The pins 40 *q* and *r* fixed on the beam *c*, bear on the levers *g* and *h*, which carry the selecting rods *e* and *f*, as in the above described machine. The springs *m* and *n* keep the levers 45 normally pressed upward against the pins *q* and *r* of the rocking beam. An abutting piece 23 stops the upward movement of the rods when they have passed through the perforations of the Wheatstone slip for a 50 purpose described below. The levers *g* and *h* also carry two rods 24 and 25, only one of which 24 can be seen in the drawing, which rods provide bearings for the heads of the "thrusters" 26 and 27. The rods 24 55 and 25 are guided in a stud 28 to prevent side motion. The thrusters 26 and 27 are two rods pivoted each to one of the arms of the three-armed lever 19 as shown. When for instance the lever *g* is raised, as shown 60 in the drawing, the rod 24 is raised also and brings the ends of the thruster 26, opposite the left end of a rod 29, called a "tapper." The total movement of the thruster in horizontal direction is considerably 65 greater than that of the corresponding

tapper, it being only at the very end of the stroke of the thruster that they come into contact. It is in order to insure that during the period of contact the thrusters should have only a horizontal motion, that 70 the levers *g* and *h* are stopped by the abutment piece 23. The tappers 29 and 30 in turn, transmit the motion of the thruster to the rocking lever *x*, which is of similar construction to that of the machine shown in 75 Fig. 1 and carries contact pins 1 and 2 electrically connected respectively, with the screws 31 and 32 which serve as contact studs for line and earth. The contact pins 1 and 2 make contact alternately with the 80 levers 5 and 6, connected respectively to the positive and negative poles of the battery, and carried on the insulating piece 10. They are kept apart by a hard steel button 33 fixed on the lever 5 and abutting on a jewel 85 fixed in the lever 6. Owing to the machine being completely motor driven greater movements can be allowed than with a machine in which active parts are only spring driven, and thus it is unnecessary to provide 90 for an adjustment for the distance between the levers 5 and 6. These are kept in contact with the pins 1 and 2 by the springs 11 and 12.

The upper arm *v* on the rocking lever is 95 beveled as to its end whereon rides a jockey pulley 15, mounted on the block 34, which can be adjusted by means of a screw 35. The abutments 13 and 14 limit the travel of the rocking lever *x* as in the old machine. 100

The main difference between the two instruments will be seen to lie principally in the means used for moving the contact making parts for reversing the current. In the new machine, the drive is a positive one 105 from the source of power of the machine through rigid mechanical links, while in the old machine, the driving power for moving the contact making parts is taken from the small springs *m* and *n*. This enables the 110 new machine to have far stouter parts, which can better resist wear and give better electric contacts. Another difference in construction which is of consequence is the arrangement of the adjustable parts. In the 115 new machine the adjustments are: the alteration of the mid position of the rocking lever, and the alteration in the amount of travel of the same. The first adjustment is effected by moving the jockey pulley block 120 34 backward or forward by means of the screw 35; the second adjustment is effected by means of the abutment screws 13 and 14. All these adjustments, it will be noted, are 125 easily accessible, and can be locked with great facility. In the old machine shown in Fig. 1, the adjustments are the "phase" at which the reversals will take place, by means of the collars *y* and *z* which are screwed on the rods *s* and *t*; and the amount 130

of travel allowed to the rocking lever α . Owing to the slenderness of the parts, the former adjustment especially is often very troublesome to effect. But most of the differences of details will be found to be on the whole one of size and dimensions; the new machine admits of larger, stronger parts, and large bearing surfaces which minimize the wear.

10 While the transmitter described is meant for use in ordinary telegraphy over lines, it is obvious that the "thrusters" which are positively driven by the motor and only controlled in their position by the perforated 15 tape can be used for effecting other work than moving contact making parts. In wireless telegraphy for instance the signals are sometimes produced by interrupting and closing oscillation circuits in which considerable amounts of energy are found, and controlling of heavy contact making and breaking parts can be effected by means of the 20 thrusters controlled by a perforated paper slip in the manner above described.

25 What I claim is:—

1. An automatic transmitter for telegraphic signals comprising a perforated

tape, contact making elements, two tappers controlling said contact making elements, a rocking beam, pins on said beam, pivotally mounted levers actuated by said pins, selecting rods on said levers coacting with said perforated tape, an abutting piece for limiting the upward movement of said selecting rods, rods depending from said levers, a 30 thruster connected to each depending rod, and means for actuating said thrusters to transmit movement through said tappers to said contact making elements.

2. An automatic transmitter for telegraphic signals comprising a perforated tape, contact making elements, pivotally mounted thrusters, means controlled from said strip for adjusting same in the vertical direction and positive means for moving 45 said thrusters in the longitudinal direction to actuate contact making elements.

In witness whereof, I have subscribed my signature, in the presence of two witnesses.

HARALD BILLE.
